THE NORRIS PETERS CO., PHOTO-LITHO., WASHINGTON, D. C.

UNITED STATES PATENT OFFICE.

ENOS CURTISS, OF FINDLAY, OHIO.

STREET-SWEEPER.

SPECIFICATION forming part of Letters Patent No. 725,939, dated April 21, 1903.

Application filed April 22, 1902. Serial No. 104,156. (No model.)

To all whom it may concern:

Be it known that I, ENOS CURTISS, a citizen of the United States, residing at Findlay, county of Hancock, and State of Ohio, have 5 invented a certain new and useful Improvement in a Combined Street Sweeper and Sprinkler, of which the following is a specification.

My invention relates to a new and useful 10 improvement in street-sweepers, and has for its object to provide a sweeper which is intended to be attached behind a wagon and the dust and dirt swept up will be carried upward and loaded into the wagon or cart preceding the sweeper.

A further object of my invention is to provide a sweeper with a reservoir for containing water and so constructed that a sprinkler is carried ahead of the revolving brush, so as 20 to prevent raising of the dust by the sweeper.

With these ends in view this invention consists in the details of construction and combination of elements hereinafter set forth and then specifically designated by the claim.

25 In order that those skilled in the art to which this invention appertains may understand how to make and use the same, the construction and operation will now be described in detail, referring to the accompanying drawings, forming a part of this specification, in which—

Figure 1 is a side elevation of my improved sweeper; Fig. 2, a vertical longitudinal section of the same; Fig. 3, a plan view; Fig. 4, a front elevation.

35 In the drawings, A represents the two main wheels of the sweeper, which are secured rigidly upon the axle B, extending transversely across the machine.

40 C represents two beams arranged upon each side of the machine, and these two beams are joined together at the rear by the cross-beam D. These side beams, together with the cross-beam D, constitute the main framework of 45 the machine, and the side beams are set at an angle slanting from the rear and are supported upon the axle B at a point midway between their ends. The framework is also supported at the rear by means of a caster-wheel E, pivoted in the center of the cross-beam D.

F is a housing arranged between the side beams C and secured thereto, and this housing is inclined upward and forward the same as the side beams, and upon the interior of 55 the housing is arranged an endless traveling belt G, which at the lower and rearward end passes around a roller H, which roller is driven upon the outside of the housing by means of a link belt I, which passes around a large 60 sprocket-wheel J, secured to the main axle B, and also around a small sprocket-wheel K, secured upon the same shaft as the roller H. At the upper and forward end of the housing F is arranged an idle roller L, around which 65 the endless belt G also passes. At the upper and forward end of the housing is arranged a downwardly-projecting chute M, and the idle roller L is so arranged that anything carried upward by the endless belt G will fall 70 into the chute M as the belt passes around the roller L.

Arranged at the rear of the housing and extending transversely across the machine and in contact with the ground is a rotary brush 75 N, which is journaled at one end in the bar O and at the other end in the frame of the machine. The bar O is in turn pivoted at the point O' to the side beam C upon that side of the machine. Upon the outer end of the shaft 80 of the rotary brush is secured a friction-wheel P, which is adapted to be held in contact when the machine is in operation with the main wheel A upon the same side of the machine as the friction-wheel P and the bar O. 85 Upon the upper end of the bar O is formed ratchet-teeth arranged in a circle concentric to the pivotal point O', and these ratchet-teeth are adapted to be engaged by a pawl Q, pivoted to a support Q', secured firmly to the 90 side beam C. This is for the purpose of holding the friction-wheel P in or out of engagement with the main wheel A.

R is a coupling by which the sweeper may be attached to a wagon or cart, and when the 95 sweeper is so attached the chute M will lie over the box of the wagon or cart, so that anything falling from said chute will fall into the body of the wagon.

It will be seen that as the sweeper is pulled 100 forward by being connected to the wagon or cart the rotary brush will be caused to revolve

by means of its friction-wheel P being in contact with the main wheel A, and this revolution will be such as to throw the dirt and dust forward into the housing F and onto the traveling apron G. This apron will then carry the dust or dirt upward and as it passes off the apron will fall through the chute M into the wagon-body.

For the purpose of preventing the raising of a dust as the sweeper passes through the streets I provide a reservoir S, which is arranged upon the machine and supported by the side beams C, and this reservoir is connected by a pipe T with a sprinkler U, arranged below the forward end of the housing F, so that the street will be sprinkled in advance of the rotary brush.

V is a valve arranged within the pipe T, and W is a valve-rod extending forward to the forward portion of the housing F and there provided with a handle, so that the valve can be opened or closed by the driver of the wagon. The rotary brush is capped, as represented at X, so as to prevent any of the dust or dirt which may cling to the brush to be thrown upward or to the rear.

The advantage of my invention is that in sweeping the street with my improved sweeper the dirt and dust is not brushed to one side to be gathered up later by carts, but is elevated at once and deposited in the cart ahead of the sweeper, and by providing the sweeper with a sprinkler attachment the great amount of dust raised by ordinary sweepers is done away with.

Of course I do not wish to be limited to the exact construction here shown, as slight modi-

fications could be made without departing from the spirit of my invention.

Having thus fully described my invention, 40 what I claim as new and useful is—

In a street-sweeper, a pair of main driving wheels rigidly mounted upon an axle, a suitable frame secured to the axle at an incline, a caster pivoted in the rear cross-beam of the 45 frame, a bar having a bearing-box at one end and ratchet-teeth arranged in a semicircle at its opposite end, said bar being pivoted intermediate its length to the frame of the sweeper, a rotary brush having one end of its 50 shaft journaled in a bearing secured to the frame and its opposite end journaled in the bearing-box on the end of the bar, a frictional wheel rigidly mounted on the end of the shaft, a post carrying a pawl secured to 55 the frame, said pawl adapted to register with the ratchet-teeth on the bar whereby the frictional wheel is held in contact with the tire of the main driving-wheel, an upwardly-inclined housing secured to the frame and 60 extending from the brush upward, a downwardly-depending chute leading from the upper end of the housing, an endless apron arranged within the housing and means for driving said apron from the main axle substantially as described.

In testimony whereof I have hereunto affixed my signature in the presence of two subscribing witnesses.

ENOS CURTISS.
